A. A. HAAHR.
PEGGING MACHINE.
APPLICATION FILED MAY 4, 1916.

1,291,487.

Patented Jan. 14, 1919.

UNITED STATES PATENT OFFICE.

ANTON AUGUST HAAHR, OF COPENHAGEN, DENMARK, ASSIGNOR, BY MESNE ASSIGNMENTS, TO UNITED SHOE MACHINERY CORPORATION, OF PATERSON, NEW JERSEY, A CORPORATION OF NEW JERSEY.

PEGGING-MACHINE.

1,291,487.

Specification of Letters Patent.

Patented Jan. 14, 1919.

Application filed May 4, 1916. Serial No. 95,366.

To all whom it may concern:

Be it known that I, ANTON AUGUST HAAHR, a subject of the King of Denmark, residing at Copenhagen, Denmark, have invented certain Improvements in Pegging-Machines, of which the following description, in connection with the accompanying drawings, is a specification, like reference characters on the drawings indicating like parts in the several figures.

This invention relates to machines for pegging boots and shoes. For the purpose of illustration the invention is shown herein as embodied in a machine of the type shown and described in United States Letters Patent No. 581,066, granted April 20, 1897, on application of John F. Davey and Sherman W. Ladd, although the utility of the invention as a whole or various features thereof 20 in connection with machines of other types is recognized.

The general object of the present invention is to provide an improved machine for inserting pegs in boots and shoes. More particularly the invention aims to provide an improved pegging machine of the type set forth in the above mentioned Letters Patent.

Machines of the type disclosed in said Letters Patent are provided with a work supporting horn on which are carried the cutters for severing the pegs and the operating mechanism for those cutters. In the illustrated machine the work supporting end 30 of the horn comprises a button or cap plate through which the ends of the pegs project after being driven, the cutters operating below the cap plate to sever the projecting ends of the pegs. It is important that the pegs should be cut off as closely as possible to the work. To accomplish this result the center portion of the horn cap plate must necessarily be as thin as practicable, and the construction and arrangement of the cutters 35 and their operating mechanism must be such as to enable them to sever the peg as nearly as possible in the plane of the cap plate. At the same time the cap plate must be sufficiently strong to resist properly the blows

of the awl and peg driver. A feature of the 50 present invention consists in a novel construction and arrangement by the use of which, without sacrificing any of the well-known advantages of prior constructions, the pegs may be cut off more closely to the 55 material through which they have been driven without in any way decreasing the resistance offered by the cap plate to the blows of the awl and peg driver.

On the contrary, in accordance with an 60 other feature of the invention the illustrated construction and arrangement are such that the horn and particularly the horn cap offers substantially greater and more effective resistance against the blows of the peg driver 65 than in machines as heretofore constructed.

It is furthermore important, especially in 70 operating upon certain kinds of work, that the transverse dimension or diameter of the upper part of the horn which is inserted in the shoe to be operated upon should be as 75 small as it can be made consistently with proper construction and operation of the peg cutters and their operating mechanism and without interfering with the proper operation of the awl. In accordance with a further feature of the invention, by reason 80 of the compact construction and arrangement of the cutters and cutter operating mechanism, the illustrated horn button and the upper part of the horn tip are substantially smaller than has heretofore been possible. This is of especial importance when the machine is used in operating upon work such, for example, as shoes having pointed 85 toes or shoes of small sizes, including particularly infants' and children's shoes. At the same time the illustrated horn is equally well adapted for operating upon shoes of large sizes.

Another feature of the invention resides 90 in the provision of cutters which are so constructed and arranged that they invariably shear off the projecting ends of the pegs cleanly and with the minimum expenditure 95 of power. It has heretofore been the practice to make horn peg cutters of wedge shape, and due to the cutters being rela-

tively thick adjacent to the cutting edges, said cutters have sometimes operated to crush the projecting ends of the pegs and to break them off rather than to cut them, thereby necessitating subsequent rasping of the points of the pegs. It has been found in practice that cutters constructed and arranged as herein illustrated and described shear off the projecting ends of the pegs so 10 cleanly that no rasping of the points of the pegs is necessary subsequent to their operation.

Another feature of the invention relates to novel means especially adapted for embodiment in a machine of the type illustrated for conveniently and accurately adjusting the peg cutting knives to compensate for wear, thus both prolonging the lives of the knives by making it practicable to use 20 knives even after they have been ground repeatedly and at the same time making it possible to obtain a clean cut even with badly worn knives.

Other features of the present invention include a novel construction and arrangement for mounting and guiding the peg cutters, improved means for mounting the horn cap on the detachable horn tip, and novel mechanism for operating the cutters yielding to 30 prevent breakage.

These and still other features and advantages of the present invention, designed to provide a pegging machine which will be stronger, simpler, and more effective in operation, and in which the parts likely to need adjustment or replacement will be constructed and arranged to be more accessible and more conveniently replaced or adjusted than has been possible heretofore, will be 40 apparent from the following detailed description read in connection with the appended drawings which illustrate a preferred embodiment of the invention incorporated in a machine of the type above mentioned.

Referring to the drawings,

Figure 1 is a side elevation of a part of a machine embodying the invention showing the horn and the horn support, the cutter operating mechanism and enough of the peg driving mechanism to make the invention readily understandable, the horn being shown partly in section.

Fig. 2 is a side elevation of the horn in 55 section;

Fig. 3 is a view in angular perspective of one of the cutter holders and the fulcrum for the cutters; and

Fig. 4 is a view in perspective of the cutters.

As hereinbefore stated, the illustrated machine is a machine of the type shown and described in the said United States Letters Patent. Conveniently, and as shown, ex-

cept as hereinafter described in detail, the 65 machine may be substantially as disclosed in said Letters Patent. Accordingly only such parts of the illustrated machine will be described hereinafter as are necessary to a clear understanding of the present invention 70 and reference should be had to the said Letters Patent for details of construction not fully set forth herein.

The machine comprises a column which supports the main framework or head A of 75 the machine. The head A carries the awl B, peg driver C and the actuating mechanism therefor, these parts, as shown, being substantially like those illustrated in the patent above mentioned. The column has 80 secured to it a horn supporting sleeve D carrying a hollow horn E comprising a main or body portion F, a tip portion G detachably secured to the body portion, as will be hereinafter explained, and a cap plate or cover 2 85 removably mounted on the top of the horn tip. The cap plate 2 has an opening 3 to receive the ends of the pegs as they are driven. The horn tip G is secured to the main or body portion of the horn by means 90 of four screws 1. The cap plate or cover 2 is provided with a dove-tail received in a dove-tailed slot in the horn tip G. For removably attaching the cap plate 2 to the horn tip G there is provided a forked piece 95 4 secured to the horn tip G by a screw 5 threaded into a part 6 in the horn tip G. In the operative relation of the parts the fork 4, by embracing the depending part of the cap plate 2 on both sides, securely holds the 100 cap plate against removal from the horn, while merely by removing the single screw 5, the cap plate 2 may be quickly and easily removed for replacement.

The cutting mechanism which is carried 105 in the top of the horn comprises knives 7 and 8 arranged to operate in a cylindrical cavity in the lower part of the cap plate or cover 2, the cap plate or cover 2 having a central aperture or opening through which 110 the awl and driver pass and through which the end of each driven peg projects, the cutters operating to cut off the ends of the pegs immediately beneath the cap plate. The knives 7 and 8 are carried upon annular 115 holders, one of which is shown at 13. The holders are loosely fulcrumed upon a fixed stud 9 located, as shown, just below the cap plate 2, the stud 9 in accordance with an important feature of the invention being 120 separated from the lower face of the cap plate 2 by a distance substantially less than the diameter of the cap plate 2 and less than the distance traversed by the cutting edge of each of the knives. The stud 9 (see Fig. 125 2) has its ends loosely received in vertical slots opening upwardly at the upper end of the horn tip. The rim of the cap plate

overlies the open upper ends of the said slots. The ends of the stud are cut away on their upper sides which are spaced from the rim of the cap plate. The bifurcated portions of the forked piece 4 pass between the rim of the cap plate and the ends of the stud 9. The forked piece 4 constitutes a common securing means for cap plate 2 and stud 9, and upon removal of piece 4 the cap plate, stud, cutter holders, and cutters may be bodily removed from the tip. The removal of the stud, cutter holders, and cutters is made possible by the loose connection shown in Fig. 2 between the cutter holders and their operating levers. The stud 9 is provided with an opening 10 through which pass the severed portions of the pegs. The knives 7 and 8 have curved cutting end portions and are shaped in a circular curve of comparatively small diameter (Fig. 4). The annular holders which, as above stated, are fulcrumed upon the stud 9 are provided with recesses to receive pins 11 and 12 by which the knives 7 and 8 respectively are mounted in the knife holders.

It will be observed that, by reason of the described construction and arrangement of the knives 7 and 8 and the knife holders with relation to each other and in respect to their fulcrum 9 and by reason of the location of the fulcrum 9 in close proximity to the cap plate 2, upon actuation of the knife holders a rocking movement is imparted to the knife holders and operative movement is thereby given to the knives 7 and 8 in directions to cause the knives 7 and 8 to approach each other in a curved path of a radius considerably smaller than the radius of curvature of the plane of the relatively flat cap plate 2. Necessarily the central portion of the cap plate 2 adjacent to its central opening must be as thin as practicable in order that the pegs may be cut off as closely to the work as possible. The construction and arrangement just described not only facilitates cutting off the pegs closer to the work by making it practicable to reduce substantially the thickness of the central portion of the cap plate but at the same time makes it possible to strengthen the cap plate materially by thickening the edge portions of the cap plate as indicated at 57, Fig. 2, thus enabling the cap plate and consequently the horn to offer a greatly increased resistance to the impacts of the awl and the blows of the driver as compared with cap plates of uniform thickness throughout. Also by reason of the great compactness of the cutter mechanism due in part to the small radius of turning movement of the cutters, the illustrated cap plate or button and the upper part of the horn tip are substantially smaller in diameter than the corresponding parts of pegging machines as heretofore constructed.

As hereinbefore stated, this greatly facilitates the operation of the machine especially when the machine is used for pegging shoes having pointed toes or shoes of small sizes, particularly infants' and children's shoes, without, however, diminishing the usefulness of the machine in operating upon shoes of even the largest sizes. At the same time and in accordance with another feature of the invention the lower surfaces of the cap plate may be and are disposed in the plane or path of movement of the knives and the fulcrum stud 9 is constructed, as shown in Fig. 3, to present an annular surface 59 substantially complementary to the lower surfaces of the cap plate, the lower surfaces of the cap plate and surface 59 constituting an arcual guideway for the cutters in which the cutters are fully supported throughout their whole operative movement. The knives 7 and 8 are formed as relatively thin blades of substantially uniform thickness throughout and with relatively short beveled cutting surfaces (see Fig. 4). The opening 3 of cap plate 2 is of slightly greater diameter than the peg to be cut. The distance between the cutting edge of each of the knives and the point of intersection of a radial line, drawn through the point where the beveled cutting surface meets the inner surface of the knife, with the outer surface of the knife is less than the radius of the opening 3 and consequently less than the radius of the peg to be cut. By reason of the above construction, the knives themselves pass into the pegs and cut them cleanly. A sharpened cutting edge can be maintained thereon by grinding down the beveled ends. For operating the knives 7 and 8 through the knife holders each knife holder has a forked extension 16, (Fig. 3) the extensions 16 being arranged to embrace respectively the ends of two levers 18 and 19 fulcrumed on a pin 55 fixed in the horn tip. The jaws 18 and 19 have extensions 20 and 21 below their fulcrum point 55, the extensions 20 and 21 of the levers 18 and 19 being crossed at 60. A fork comprising two flat arms 28 carries three rolls 22, 23 and 24 fulcrumed respectively on pins 25, 26 and 27, the rolls 23 and 24 being located, as best shown in Fig. 2, to engage the outer sides of the extensions of the members 20 and 21 substantially at the point of crossing of these levers and the roll 22 being disposed in the opening between the members 18 and 19 just below their pivot 55 to have wedging engagement with the extensions of the members 18 and 19 upon their inner sides. The fork 28 is reciprocated by a rod 29 guided in the cylindrical part 30 of the horn. On one end the rod 29 carries a pin 31 carrying a roll, said pin passing through an oval slot 32 in a triangular piece 33 fulcrumed upon a pin 34 in the horn. The triangular piece

33 is provided with another oval slot 35 through which passes a pin 37 carrying a second roll, the pin 37 being attached to the end of a rod 36 and the opening in the horn 5 through which the triangular piece 33 moves being closed by a cap 38 screwed to the horn. The rod 36 which is guided in the hollow column of the horn is hinged to a link 39 adjustably connected to an operating rod 51.

10 Upon movement of the rod 51 the rod 36 is operated through its described connection with the triangular piece 33 to rock the member 33 about its fulcrum 34; thereby reciprocating the rod 29. Movement of the

15 rod 29 one way operates by means of the rolls 23 and 24 to draw the lower ends of the extensions 20 and 21 toward each other, thereby separating the jaws 18 and 19 and rocking the knife holders about their ful-

20 crum stud 9 to impart relative cutting movement to the knives 7 and 8 in timed relation to the peg driving mechanism to cause the knives to cut off the projecting end of a driven peg close to the under side of the

25 cap plate 2.

To provide for ready adjustment of the normal position of the knives relatively to each other to alter the limit of normal approach of the knives and thereby, for example, by moving the knives nearer together to compensate for wear of the knives, as above stated, an adjustable connection is provided between the link 39 and the rod 51. In the illustrated construction this adjustable connection comprises a head piece 40 to which the link 39 is pivotally connected, which head piece is hollow and receives a screw 42 surrounded by a spring 41, the upper end of the screw having a projecting head 43 by which it may readily be turned to effect the desired adjustment through an opening in the horn normally covered by a cap 52. A milled flange 44 is carried by said screw 42 below the head 43, and the head piece 40 is provided with internal projections 44'. A block 48 disposed in the horn cavity and free to move vertically but secured against turning movement is threaded to receive the screw 42. The lower end of the block 48 comprises a fork 49 the arms of which are connected by a stud 50 to which the operating rod 51 above mentioned is pivoted.

Upon turning the projecting head of the screw 42 and consequent movement of the screw 42 relatively to the block or nut 48 the distance between the head piece 40 and the nut 48 may be varied as desired, thereby increasing or diminishing the effective length 55 of the operating parts through which the triangular piece 33 is rocked, whereby the normal distance between the cutting edges of the knives 7 and 8 can be varied. This enables the knives to be adjusted to com-

pensate for wear and insures clean cutting 65 even when the knives have been badly worn or greatly ground down.

The spring 41 provides a yield for the knife operating mechanism whereby, if the knives encounter any abnormal or unexpected obstacle before they have completed a cutting movement, the spring 41 will yield to prevent damage as, for example, in the event that an awl breaks and a part of the awl remains between the knives. The reverse movement of the knives is effected by the engagement of milled flange 44 with projections 44'.

The head piece 40 has a horizontal projection 46 provided with a hole in which is 80 carried a spring pressed plunger 47 normally pressed into engagement with the milled flange 44 by a spring 45 thus preventing accidental turning of the screw while permitting the screw to be readily turned 85 by its head 43.

Having fully described the invention, what is claimed as new and desired to be secured by United States Letters Patent is:

1. In a pegging machine, in combination, 90 a horn, a horn cap or cover having a central opening for an awl, cutters operating in the top of the horn beneath the horn cap, a fulcrum for the cutters, cutter holders for operating the cutters, and mechanism for operating the cutter holders, said cutters and said fulcrum being constructed and arranged 95 relatively to said cap plate to cause the relative movement of the cutters to be along a path the radius of curvature of which is 100 substantially less than the diameter of the cap plate.

2. In a pegging machine, in combination, 105 a horn, a horn cap or cover having a central opening for an awl and having a portion of its lower surface curved, cutting means operating in the top of the horn beneath the horn cap and mounted for movement adjacent to the curved surface of the horn cap and concentrically therewith, a fulcrum for 110 the cutting means, and mechanisms for operating the cutting means, the fulcrum for said cutting means being disposed below said cap plate a distance less than that traversed by the edge of the cutting means upon operation of said means.

3. In a pegging machine, in combination, 120 a horn, a horn cap or cover having a central opening for an awl and having a portion of its lower surface curved, cutters operating 125 in opposite directions in the top of the horn beneath the horn cap and mounted for movement adjacent to the curved surface of the horn cap, a fulcrum for the cutters, cutter holders for operating the cutters, and mechanism for operating the cutter holders, said fulcrum for the cutters being disposed below said cap plate a distance less than the length 130

- of the lower surface of the horn cap adjacent to which the cutters move.
4. In a pegging machine, in combination, a work supporting horn, a horn cap or cover having a central opening for the projection of a driven peg, cutters operating in the top of the horn beneath the horn cap, holders for the cutters constructed and arranged to impart to the cutters relative rocking movement, a fulcrum for the cutter holders, and means for operating the cutters through the cutter holders, said cutters having their inner surfaces formed concentrically of the surface of said fulcrum and being mounted directly on said fulcrum and confined in their movements between the fulcrum and the surface of the horn cap so that the operating movement of the cutters takes place along a curved path of substantially minimum radius of curvature.
5. In a pegging machine, in combination, a horn, a horn cap or cover having a central opening for the projection of a driven peg, a fulcrum member inclosed by and spaced from the walls of the horn and mounted in the top of the horn closely adjacent to the lower surface of the cap plate, a cutting blade mounted directly on said fulcrum member and confined in its movements by the surfaces of the fulcrum and horn cap, and means for operating the cutting blade.
6. In a pegging machine, in combination, a horn, a horn cap or cover having a central opening for the projection of a driven peg, cutters fulcrumed in the top of the horn beneath the horn cap for relative cutting movement in a curved path, the fulcrum surfaces of the cutters being located at a distance from the cap plate less than the diameter of the opening of the cap plate, and means for operating the cutters.
7. In a pegging machine, in combination, a horn, a horn cap or cover having a central opening for the projection of a driven peg, cutters fulcrumed in the top of the horn beneath the horn cap for relative cutting movement in a curved path, the axis of the fulcrum of each of the cutters being at a distance from the cap plate substantially less than the diameter of the fulcrum, and means for operating the cutters.
8. In a pegging machine, in combination, a horn, and a horn cap or cover having an opening for the projection of a driven peg, a substantially flat upper surface, and a curved lower surface and being relatively thin near the opening, the radius of curvature of the lower surface being less than twice the diameter of the cap opening whereby the marginal portions of the cap are thickened to increase the resistance of the horn to the blows imparted thereon in the operation of the pegging machine, a cutter carried in the top of the horn below the horn cap, and means for moving the cutter along a path adjacent to and substantially concentric with the curved lower surface of the horn.
9. In a pegging machine, in combination, a horn, a horn cap or cover having an opening for the projection of a driven peg, a substantially flat upper surface, and a curved lower surface and being relatively thin near the opening, the radius of curvature of the lower surface being less than twice the diameter of the cap opening whereby the marginal portions of the cap are thickened to increase the resistance of the horn to the blows imparted thereon in the operation of the pegging machine, cutters carried in the top of the horn below the horn cap, and means for moving the cutters toward and from each other along paths adjacent to and substantially concentric with the curved lower surface of the horn cap.
10. In a pegging machine, in combination, a horn, a horn cap or cover, cutters carried in the top of the horn below the horn cap, holders for the cutters mounted for rocking movement to effect operating movement of the cutters in a curved path, means for operating said cutters through said holders, and a fulcrum engaging the holders and cutters, said horn cap and said fulcrum being relatively constructed and arranged to provide an arcual guideway for the cutters.
11. In a pegging machine, in combination, a horn, a horn cap or cover, cutters carried in the top of the horn below the horn cap, holders for the cutters mounted for rocking movement to effect operating movement of the cutters in the arc of a circle, means for operating said cutters through said holders, and a fulcrum engaging the holders and cutters, said cap plate having a thin central portion and thickened edge portions constructed and arranged to present their lower surfaces in the plane of movement of the cutters, and said fulcrum having a peripheral contour substantially complementary to the plane of the lower surfaces of the edge portions of the cap plate whereby an arcual guideway is formed for the cutters.
12. In a pegging machine, in combination, a horn, a horn cap or cover having an opening for the projection of a driven peg, a fulcrum member spaced from the lower surface of the horn cap, cutting means mounted in the top of the horn and comprising a cutting blade mounted directly on the fulcrum member and operating to sever the projecting end of the peg, and means for operating the cutting blade comprising a member pivoted upon said fulcrum member independently of the cutting blade and operatively connected to the cutting blade.
13. In a pegging machine, in combination, a horn, a horn cap or cover having an open-

ing for the projection of a driven peg, cutters mounted in the top of the horn, means for operating the cutters toward and from each other to sever the projecting end of the peg, and a fulcrum for the cutters, said fulcrum being cut away to permit the discharge of the severed portion of the peg.

14. In a pegging machine, in combination, a horn, a horn cap or cover having an opening for the projection of a driven peg, cutters mounted in the top of the horn, means for operating the cutters toward and from each other to sever the projecting end of the peg, and a fulcrum for the cutters, said fulcrum having an opening therethrough to permit the discharge of the severed portion of the peg.

15. In a pegging machine, in combination, a horn, a horn cap or cover having an opening for the projection of a driven peg, cutters mounted in the top of the horn, means for operating the cutters toward and from each other to sever the projecting end of the peg, and a fulcrum for the cutters, said fulcrum having an opening therethrough in vertical alinement with the opening in the cap plate to permit the discharge of the severed portion of the peg.

16. In a pegging machine, in combination, a horn having an opening in the top thereof for the projection of a driven peg, cutters mounted in the top of the horn beneath the opening for relative cutting movement in a curved path, pivoted holders upon which the cutters are mounted, lateral projections on the cutters for securing the same to the holders, the cutters being formed as blades of substantially uniform thickness having beveled cutting portions, and means for operating the holders, the support for the cutters afforded by said lateral projections permitting the same to be forced into the peg beyond the beveled portions thereof.

17. In a pegging machine, in combination, a horn having an opening in the top thereof for the projection of a driven peg, cutters mounted in the top of the horn beneath the opening for relative cutting movement in a curved path, pivoted holders upon which the cutters are mounted, lateral projections on the cutters for securing the same to the holders, the cutters being formed as relatively thin blades of substantially uniform thickness having beveled cutting portions, and means for operating the holders, the support for the cutters afforded by said lateral projections permitting the same to be forced into the peg beyond the beveled portions thereof.

18. In a pegging machine, in combination, a horn having an opening in the top thereof for the projection of a driven peg, cutters mounted in the top of the horn beneath the opening for relative cutting movement

in a curved path, pivoted holders upon 65 which the cutters are mounted, a fulcrum member having bearings for the holders at each side of its middle portion and being annularly raised at its middle portion, the cutters being supported by and moving on 70 the raised middle portion, means for securing one of the cutters to one of the holders and the other cutter to the other holder, and means for operating the holders.

19. In a pegging machine, in combination, 75 a horn having an opening in the top thereof for the projection of a driven peg, cutters mounted in the top of the horn beneath the opening for relative cutting movement in a curved path, pivoted holders 80 upon which the cutters are mounted, a fulcrum member having an enlarged portion and having parts extending beyond each end of the enlarged portion, said extensions forming bearings for the holders, shoulders 85 provided on the holders adapted to engage the ends of the enlarged portion and rims on the holders fitting over the ends of the enlarged portion, the cutters being supported by and moving on the enlarged portion, 90 means on the rims for actuating the cutters when the holders are actuated, and means for actuating the holders.

20. In a pegging machine, in combination, 95 a horn cap having an opening therein for the projection of a driven peg, a stationary fulcrum member spaced from the lower surface of said cap, cutting means beneath the top of the horn in juxtaposition thereto and comprising cutting blades having beveled cutting edges and shaped to the rear of the cutting edges to fit said fulcrum member, and means for operating the blades toward and from each other to shear off the projecting ends of the pegs.

100 21. In a pegging machine, in combination, a horn cap having an opening therein for the projection of a driven peg, a stationary member spaced from the lower surface of said cap, means for cutting off the projecting portion of the peg comprising knives of substantially uniform thickness mounted directly on said member and having beveled cutting ends adapted when 105 operated to shear off the projecting portion of the peg, and means for moving the knives toward and from each other.

110 22. In a pegging machine, in combination, a horn cap having an opening therein for the projection of a driven peg, a stationary member spaced from the lower surface of said cap, means for cutting off the projecting portion of the peg comprising knives of substantially uniform thickness mounted directly on said stationary member 115 and confined in their movements between the surface of said member and the lower surface of the cap and having relatively 120 125

short beveled cutting ends adapted to shear off the projecting portions of the pegs, and means for moving the knives toward and from each other.

23. In a pegging machine, in combination, a horn cap having an opening in the top thereof for the projection of a driven peg, a stationary fulcrum member spaced from the lower surface of said cap, means for cutting off the projecting portion of the peg comprising curved knives of substantially uniform thickness mounted directly on said fulcrum member and having their end portions beveled to an extent less than the radius of the cap opening to permit portions of the body parts of the knives to pass into the peg in the severance of the same whereby a clean cut is effected, and means for moving the knives toward and from each other.

24. In a pegging machine, in combination, a horn cap having an opening therein for the projection of a driven peg, a stationary fulcrum member spaced from the lower surface of said cap, means for cutting off the projecting portion of the peg comprising curved knives of substantially uniform thickness mounted directly on said fulcrum member and confined in their movements between the horn cap and fulcrum member and having beveled cutting end portions, the distance between the cutting edge of each of the knives and the point of intersection of a radial line, drawn through the point where the beveled cutting surface meets the inner surface of the knife, with the outer surface of the knife being less than the radius of the cap opening, and means for moving the knives toward and from each other.

25. In a pegging machine, in combination, a horn cap having an opening therein for the projection of a driven peg, a stationary fulcrum member spaced from the lower surface of said cap, means for cutting off the projecting portion of the peg comprising curved knives of substantially uniform thickness mounted directly on said fulcrum member and having beveled cutting ends, and means for moving the knives toward and from each other.

26. In a pegging machine, in combination, a horn comprising a main body portion and a horn tip open at the top and having open-ended slots, a cap plate closing the top of the horn tip and over-lying the ends of the slots, said cap plate also having an opening for the projection of a driven peg, a supporting member mounted in said slots, cutting mechanism mounted on said supporting member for operation on the projecting tip of the peg whereby the supporting member and cutting mechanism may be bodily removed from the horn tip

upon removal of the cap plate, and means 65 for securing the supporting member in position.

27. In a pegging machine, in combination, a horn comprising a main body portion and a horn tip, a cap plate on the end of the 70 horn tip provided with an opening therethrough, cutters operating beneath the opening, a fulcrum for the cutters, vertical slots formed in the top side walls of the horn tip to receive loosely the ends of the 75 fulcrum, and common securing means for the cap plate and fulcrum.

28. In a pegging machine, in combination, a horn comprising a main body portion and a horn tip, a cap plate on the end of the 80 horn tip provided with an opening therethrough, cutters operating beneath the opening, a fulcrum for the cutters, vertical slots formed in the top side walls of the horn tip to receive loosely the ends of the fulcrum, 85 and a member provided with portions which pass over the ends of the fulcrum to secure the same in the slots and provided with another portion which locks the cap plate in position.

29. In a pegging machine, in combination, a support, a horn, cutters operating in the top of the horn, the horn comprising a vertical portion whereby it is secured upon the support, an inclined portion, and a reversely 95 inclined portion, and means for operating the cutters including a yielding rod and sleeve connection comprising a member adjustably connecting said rod and sleeve and presenting a part located within the lower 100 end of the first-mentioned inclined portion and constructed and positioned for manipulation to adjust the rod and sleeve relatively to each other, a portion of the wall of the horn being cut away at the upper side 105 of the first-mentioned inclined portion to permit access to said member for purposes of adjustment.

30. In a pegging machine, in combination, a horn, cutters operating in the top of 110 the horn, holders for operating the cutters pivotally supported transversely of the horn, a reciprocating member, a connection between said reciprocating member and said holders for operating the holders in one 115 direction upon movement of said reciprocating member one way and other connections between said reciprocating member and said holders for operating said holders reversely upon return movement of the reciprocating member whereby said cutters are moved in and out.

31. In a pegging machine, in combination, a horn, cutters operating in the top of 125 the horn, holders for operating the cutters pivotally supported transversely of the horn, said holders having crossed downward extensions, an operating member, and slid-

ing connections between said operating member and said extensions of the holders operating by engagement with the outer sides of said extensions to move said holders 5 one way upon movement of the operating member in one direction and other connections between said operating member and said extensions of the holders operating by wedging engagement with the inner sides of 10 said extensions to move said holders oppositely upon reverse movement of said operating member.

32. In a pegging machine, in combination,

a horn comprising a main body portion, a horn tip detachably secured to said body portion, a cap plate or cover on the end of said horn tip, said cap plate being dovetailed in said horn tip, and a member for securing said cap plate to said horn tip having a fork at one end constructed and 20 arranged to embrace the horn cap to lock said horn cap on the horn tip.

In testimony whereof I have signed my name to this specification.

ANTON AUGUST HAAHR.
